DESIGN FOR A FOOT EXERCISING FOOTREST

Joseph Fehn, San Antonio, and Bernhard
Schmidt, La Grange, Tex.

Application July 1, 1936, Serial No. 63,603

Term of patent 14 years

To all whom it may concern:

Be it known that we, Joseph Fehn and Bernhard Schmidt, citizens of the United States, residing at San Antonio and La Grange, respectively, in the counties of Bexar and Fayette, respectively, and State of Texas, have invented a new, original, and ornamental Design for a Foot Exercising Footrest, of which the following is a specification, reference being had to the accompanying drawing, forming part thereof.

Figure 1 is a perspective view of the foot exercising footrest, showing our design; and

Figure 2 is an rear view thereof, on a reduced scale.

The invention comprises an ornamental base and multiple roller equipped frame coordinated therewith.

We claim:—

The ornamental design for a foot exercising footrest, as shown and described.

JOSEPH FEHN.
BERNHARD SCHMIDT.
